MUSICAL INSTRUMENT

Gerard Thifault, 12164 Notre-Dame St. E., Pointe aux Trembles, Montreal, Quebec, Canada
Filed Jan. 12, 1961, Ser. No. 82,312
5 Claims. (Cl. 84—418)

The present invention relates to a musical instrument of the general class of the tambourine, for producing rhythmical sounds or noises in a new manner for the accompaniment of a new type of dance.

A more specific object of the invention resides in the provision of a musical instrument of the character described which is capable of producing two different sets of rhythmical sounds, one set of sounds being a series of a quick succession of sharp noises, while the other set of sounds being produced by cymbal elements so arranged as to make two beats quickly succeeding each other.

Another object of the invention resides in the provision of an instrument of the character described which is relatively inexpensive and simple to manufacture and which can be easily played by musicians accustomed to play conventional percussion instruments.

The foregoing and other important objects of the present invention will become more apparent during the following disclosure and by referring to the drawings, in which:

FIGURE 1 is a perspective view of the instrument of the invention;

FIGURE 2 is a top plan view in which the top wall has been cut off to show the inside elements;

FIGURE 3 is a bottom plan section taken through line 3—3 of FIGURE 5;

FIGURE 4 is a cross section of a modification;

FIGURE 5 is an enlarged longitudinal section taken along line 5—5 of FIGURE 2;

FIGURE 6 is a partial cross-section taken along line 6—6 of FIGURE 5; and

FIGURE 7 is an exploded perspective view of a cymbal element.

Referring now more particularly to the drawings, in which like reference characters indicate like elements throughout, the instrument of the invention comprises a closed rectangular box made of corrugated sheet metal and in which are disposed cymbal elements which are actuated by a lever projecting from the box to thereby produce the main set of rhythmical sounds. The other set of sounds is produced by sliding a hard object such as a piece of metal on the corrugations of the box.

The box 1 is completely closed comprising a top 2, side walls 3 and a bottom wall 4. At least the top 2 will be made of corrugated sheet metal. A reinforcing band 5 is disposed within the center portion of the box and is applied against the top, bottom and longitudinal side walls. A handle 6 is secured to the box 1 and projects laterally therefrom being preferably directly secured inside the box to band 5. Thus, the box can be held in one hand by handle 6.

Alternately, the box can be provided with a support or pedestal 7 secured to the bottom 4 of the box at the center thereof, as shown in FIGURE 4, in which case handle 6 is no longer used and can be dispensed with.

A transversely extending rod or shaft 8 is secured inside the box to the lateral legs 5' of the band 5 and is parallel to the top 2.

A first plate 9 of generally curved contour with a straight edge 9' is disposed within the box 1 and is provided near edge 9' with downward ears 10 having holes 10' for the passage of rod 8 whereby plate 9 is pivoted on rod 8 near its transverse edge 9'.

A curved actuating lever 11 is riveted or otherwise se-

2

cured to the top of plate 9 and passes freely through an aperture 12 made in the top 2 to extend over said top in spaced relationship therewith. A plurality of cymbal elements 13 are loosely mounted on plate 9; said cymbal elements may consist for instance of a flanged disc 14 (see FIGURE 6 for a cross-section thereof) loosely connected to sheet metal pieces 15 by connection rod 16 passing through plate 9 and having a head 17 at one end and provided with a riveted washer 18 at the other end. Disc 14 is disposed on top of the plate while pieces 15 are disposed underneath the same. Obviously other types of cymbal elements may be provided for mounting on plate 9.

It will be understood that upon a quick depression of the portion of lever 11 disposed above top 2, plate 9 will pivot upwardly in a sudden movement to thereby cause the cymbal elements 13 to produce a sound or noise.

A second plate 19, having curved contour and a straight transverse edge 19' is hung from the first plate 9 in cantilever fashion and extends opposite the said first plate 9 within box 1. The outer free portion of said second plate 19 is provided with cymbal elements 13 similar to those just described in relation with first plate 9.

The second plate 19 is suspended from the first plate 9 through the intermediary of connecting rods 20 passing through the two plates and provided at their outer ends with riveted washers 21. A pair of opposed flanged discs 14, identical with flanged discs 14 of the cymbal elements 13, are disposed between the second plate and the lower washer 21. The connecting rods 20 form a loose connection for the second plate on the first plate and the inner transverse edge 19' of the second plate abuts against the underside 9' of the first plate 9. Thus, the two plates can pivot upwardly with respect to each other but relative downward pivotal movement is limited to the rest position shown in FIGURE 5. In this position lever 11 abuts against the inner edge of slot 12.

A piece 22 of corrugated sheet metal bent into a U or any other hard element can be used for riding the same on the corrugated top 2.

The instrument of the present invention is used as follows:

The box 1 is held in one hand by handle 6 while piece 22 is held in the other hand. The piece 22 is slid along the corrugated top 2 to produce a quick succession of sharp noises and then the hand is turned and the lever 11 is quickly depressed by the back of the hand so as to produce a first beat made by the cymbal elements 13 mounted on the first plate 9 in turn quickly succeeded by a second beat made by the cymbal elements mounted on the two plates. The plate 19 pivots downwardly when its inner edge 19' is released by the already upwardly moving first plate 9 and the second beat is produced when edge 19' strikes plate 9 during downward return movement of the latter.

The entire instrument can be shaken by handle 6 to thereby produce a more or less continuous sound made by the cymbal elements without the beat characteristic produced when lever 11 is quickly depressed.

When the box 1 is mounted on pedestal 7, then the two hands are free to operate lever 11 and the striker piece 22.

While a preferred embodiment in accordance with the present invention has been illustrated and described, it is understood that various modifications may be resorted to without departing from the spirit and scope of the appended claims.

What I claim is:

1. A musical instrument for producing rhythmical sounds comprising a box having a top, side walls, and a bottom wall, a first plate disposed within said box and pivotally mounted therein adjacent an edge of said first plate, a lever rigidly secured to said first plate and ex-

tending away from said plate and through a slot in the top of said box and above said top, whereby depression of said lever will cause pivotal movement of said first plate within said box, cymbal elements loosely mounted on said first plate to produce a sound upon pivotal movement of said first plate, a second plate loosely suspended from said first plate near an edge of said second plate and extending away therefrom so as to pivot relative to said first plate, and cymbal elements loosely mounted on said second plate.

2. An instrument as claimed in claim 1, wherein at least the top of said box is made of corrugated material to provide a series of closely spaced transverse corrugations and a hard piece adapted to be slid along said corrugations to produce sounds

3. An instrument as claimed in claim 1, wherein said second plate is suspended from said first plate by connecting rods passing through said two plates, said edge

of said second plate abutting against the underside of said first plate and said lever abutting against an edge of said slot in the rest position of said two plates.

4. An instrument as claimed in claim 1, further including a laterally outwardly projecting handle secured to said box for holding said box.

5. An instrument as claimed in claim 1, further including a pedestal on top of which said box is mounted.
